US00D951731S

(12) **United States Design Patent** (10) Patent No.: **US D951,731 S**
Blumenthal et al. (45) Date of Patent: **** May 17, 2022**

(54) **PLIERS**(71) Applicant: **Milwaukee Electric Tool Corporation**,
Brookfield, WI (US)(72) Inventors: **Aaron S. Blumenthal**, Shorewood, WI
(US); **Christopher S. Hoppe**,
Cedarburg, WI (US); **Aaron M.**
Williams, Milwaukee, WI (US)(73) Assignee: **Milwaukee Electric Tool Corporation**,
Brookfield, WI (US)(**) Term: **15 Years**(21) Appl. No.: **29/765,030**(22) Filed: **Jan. 5, 2021**

CLAIM

We claim the ornamental design for pliers, as shown and described.

DESCRIPTION

FIG. 1 is a perspective view of the first embodiment from above of the claimed design;

FIG. 2 is a perspective view from below of the claimed design of FIG. 1;

FIG. 3 is a front view of the claimed design of FIG. 1;

FIG. 4 is a rear view of the claimed design of FIG. 1; FIG. 5 is a left side view of the claimed design of FIG. 1; FIG. 6 is a right side view of the claimed design of FIG. 1; FIG. 7 is a top view of the claimed design of FIG. 1; and FIG. 8 is a bottom view of the claimed design of FIG. 1. FIG. 9 is a perspective view from above of the second embodiment of the claimed design; FIG. 10 is a perspective view from below of the claimed design of FIG. 9; FIG. 11 is a front view of the claimed design of FIG. 9; FIG. 12 is a rear view of the claimed design of FIG. 9; FIG. 13 is a left side view of the claimed design of FIG. 9; FIG. 14 is a right side view of the claimed design of FIG. 9; FIG. 15 is a top view of the claimed design of FIG. 9; and FIG. 16 is a bottom view of the claimed design of FIG. 9. FIG. 17 is a perspective view from above of the third embodiment of the claimed design; FIG. 18 is a perspective view from below of the claimed design of FIG. 17; FIG. 19 is a front view of the claimed design of FIG. 17; FIG. 20 is a rear view of the claimed design of FIG. 17; FIG. 21 is a left side view of the claimed design of FIG. 17; FIG. 22 is a right side view of the claimed design of FIG. 17; FIG. 23 is a top view of the claimed design of FIG. 17; and, FIG. 24 is a bottom view of the claimed design of FIG. 17. The broken lines shown are included for the purposes of illustrating portions of the pliers that form no part of the claimed design.
